(57) **CLAIM**

The ornamental design for a display screen or portion thereof with graphical user interface, as shown and described.

DESCRIPTION

FIG. 1 is a front view of a display screen or portion thereof with graphical user interface, showing the new design; FIG. 2 is a front view of a second embodiment thereof; FIG. 3 is a front view of a third embodiment thereof; FIG. 4 is a front view of a fourth embodiment thereof; FIG. 5 is a front view of a fifth embodiment thereof; FIG. 6 is a front view of a sixth embodiment thereof; FIG. 7 is a front view of a seventh embodiment thereof; and, FIG. 8 is a front view of an eight embodiment thereof. The portions shown in broken lines depicting the display screen, text, and other graphical elements are included to show environmental unclaimed subject matter and do not form part of the claimed design.

1 Claim, 8 Drawing Sheets
